CLAIM

The ornamental design for a band as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevation view a band;

FIG. 2 is a rear view thereof;

FIG. 3 is an enlarged view of a portion of FIG. 2; and,

FIG. 4 is an enlarged view of FIG. 1.

The dot-dash broken lines in the figures and the areas within the dot-dash broken lines show portions of the band that form no part of the claimed design.

The dot-dot-dash broken lines in FIGS. 1 and 2 show the areas depicted in FIGS. 3 and 4, and form no part of the claimed design.
